[57] ABSTRACT

This disclosure depicts a number of embodiments of lightweight, highly maneuverable, friction-driven ground and floor cleaning apparatus. Lightweight, multi-function housing means serves to support for rotation a cylindrical brush and a pair of drive wheels of smaller diameter than the brush. The apparatus has two operating modes - an "upright" mode wherein the apparatus has a first set of operating characteristics including a relatively high handle operating position, and an "inverted" mode wherein the apparatus has a second set of operating characteristics, including a relatively low handle operating position.

FRICITION-DRIVEN ROTARY CLEANING APPARATUS HAVING PLURAL OPERATING MODES

CROSS REFERENCE TO RELATED APPLICATION

This application relates to but is not dependent upon my copending application Ser. No. 117,937, filed Feb. 23, 1971.

BACKGROUND OF THE INVENTION

The prior art expounds many friction-driven rotary brush devices for cleaning streets, floors, and other surfaces. Many of these devices are large, cumbersome, three and four-wheeled vehicles. All are relatively heavy, unwieldy, and otherwise generally unsuited for rapid and easy light outdoor or industrial ground and floor cleaning and clearing. An example of such prior art is the U.S. Pat. to Taft U.S. Pat. No. 588,250.

OBJECTS OF THE INVENTION

It is a primary object of this invention to provide improved friction-driven cleaning apparatus for cleaning patios, sidewalks, driveways, industrial floors, and the like which has very high cleaning efficiency, and which is extremely lightweight, compact, maneuverable, and generally easy and convenient to use.

It is another object to provide such sweeping apparatus with a friction-driven rotary brush the bite of which is capable of continuous and instantaneous adjustment while the apparatus is in use in order to compensate for variations in the characteristics of the debris being swept and of the surface being cleaned.

It is still another object to provide sweeping apparatus of the general nature described above which has two modes of operation — namely a first mode wherein the apparatus is in an "upright" attitude and has a relatively high handle elevation, and a second mode wherein the apparatus is in an "inverted" attitude and has a relatively low handle elevation.

It is yet another object of this invention to provide improved friction-driven cleaning apparatus capable of accommodating users of different heights.

Further objects and advantages of the invention will in part be obvious and will in part become apparent as the following description proceeds. The features of novelty which characterize the invention will be pointed out with particularity in the claims annexed to and forming a part of this specification.

BRIEF DESCRIPTION OF THE DRAWINGS

For a fuller understanding of the invention, reference may be had to the following detailed description taken in connection with the accompanying drawings wherein:

FIG. 1 is a perspective view of sweeping apparatus embodying this invention;

FIG. 1A is a perspective view of a bracket constituting part of the FIG. 1 apparatus;

FIG. 2 is a fragmentary front elevational view, partly broken away, of the right end of the FIG. 1 apparatus;

FIG. 3 is a fragmentary elevational view of the right end of the FIG. 1 apparatus shown in its "upright" operating mode as in FIG. 1;

FIG. 4 is a fragmentary end elevational view of the left end of the FIGS. 1-3 apparatus, the apparatus being shown in its "inverted" operating mode;

FIGS. 5 and 6 are fragmentary end and front elevational views of the right end of another embodiment of the invention; and

FIG. 7 is a fragmentary front perspective view of the FIGS. 5-6 embodiment.

DESCRIPTION OF THE PREFERRED EMBODIMENTS

FIGS. 1-4 illustrate a sweeping device 10 representing one of the many devices contemplated for implementing the principles of this invention. The device 10 is illustrated as including a support structure in the form of a housing 12 which may be, for example, of molded plastic or, as shown, of stamped sheet metal. The housing 12 supports for rotation a cylindrical brush 14 and wheels 16, 17.

The wheels 16, 17 are carried on stub axles 18, 19. The wheels 16, 17 are shown as each including a hub 20 having a peripheral depression for receiving an elastic tire 22 of high friction material.

Transmission means are provided for coupling at least one of the wheels 16, 17 and the brush shaft 15 of brush 14 such that rotation of the wheels effects an opposite rotation of the brush 14. In the FIGS. 1-4 embodiment the transmission means is shown as taking the form of a pair of spur gears 24, 26. Spur gear 24 may be affixed, for example, on the stub axle 19 of wheel 17, or alternatively, as shown, the wheel 17, stub axle 19, and spur gear 24 may be injection molded as a unitary structure from a suitable plastic material. Spur gear 26, which may also be of a molded plastic construction, is mounted on the brush shaft 15. The spur gear 26 may be formed as an integral part of a hollow sleeve which is interference fit upon the right end of the brush shaft 15. A sleeve 28 may be interference fit on the left end of shaft 15. The brush 14 is here shown as being of a construction known as "twisted-in-wire"; however, the brush may be of the tufted-axle, or strip types or of any other suitable construction.

The construction and functions of the housing 12 will now be discussed. The housing 12 has a number of significant functions. First, it provides a rigid but lightweight exoskeleton for the device and includes support structures which rotatably support the ends of the brush shaft 15 and the stub axles 18, 19 carrying the wheels 16, 17. More particularly, the housing 12 includes a longitudinal body portion 34 having a lightweight, thin-walled construction, which may be of suitable molded plastic or, as illustrated, of sheet metal. The body portion 34 of the housing 12 has a substantial curvature in planes transverse to the brush shaft 15 to provide rigidity without a high weight factor.

The housing 12 has a pair of end walls 38, 40 extending forwardly from the longitudinal body portion 34 of the housing 12. Support structures are provided to rotatably support the cylindrical brush 14 and the stub axles 18, 19 of wheels 16, 17. In the illustrated embodiment the support structures comprise brackets 42, 44 which may be affixed to the body portion 34 of the housing 12 by welding, with rivets or other fasteners or by any other suitable fastening means. See particularly FIG. 1A which illustrates clearly bracket 44. The brackets 42, 44 comprise back portions from which extend forwardly arms 45, 46 and 47, 48, respectively.

The arms 45-48 have apertures (49, 50 in bracket 44) which receive and serve as bearings for stub axles 18, 19 on the wheels 16, 17. An aperture 52 in each of

the arms 46, 47 supports for rotation the ends of brush shaft 15.

In the preferred embodiment illustrated, the brackets 42, 44 support the wheels 16, 17 on a common wheel axis 53 located forwardly of and parallel with the brush shaft 15.

A handle 54 for the device 10 is connected to the housing 12 such that the handle and the housing 12 pivot together about the common wheel axis 53. By the described construction, elevational adjustment of the handle 54 effects an adjustment of the interference between the brush and the surface being cleaned. A user may thus control the "bite" of the brush 14 instantaneously and continuously while operating the brush to compensate for variations in characteristics of the debris being swept and of the surface being cleaned.

Location of the wheel axis 53 forwardly of the brush shaft 15 has the effect that adjustment of the handle height produces an adjustment in a like direction of the brush 14. For example, lowering the handle produces a natural lowering of the brush 14, making adjustment of the brush bite a very natural maneuver.

In addition to providing structural rigidity for the device and supporting the brush 14 and wheels 16, 17 for rotation, the housing 12 also serves to shield the user from flying debris, especially if the device should be pulled backwards so as to cause the brush 14 to rotate in the reverse direction, causing the brush 14 to throw debris toward the user. The housing 12, by virtue of its wrap-around construction provides a pair of forward and rear support edges 56, 58 which protect the brush, for example, in a situation where an elevated patio is being cleaned and one wheel runs off an edge.

Friction-driven cleaning apparatus including novel exoskeletal support means, as described above, is another invention of mine disclosed and claimed in my above-referenced copending application.

In accordance with this invention, the device 10 has two modes of operation, especially intended to accommodate users of different height. In a first mode of operation (shown in FIGS. 1-3) the device 10 has a first attitude, herein termed the "upright" attitude (for convenience of explanation only) wherein the handle is in a relatively high position. In this upright attitude the device is especially suited for use by persons of average and taller than average height. To convert to a second mode of operation, the device 10 may be inverted. In this "inverted" attitude (shown in FIG. 4) the handle assumes a relatively low position. In this inverted (low handle) attitude the device 10 is especially suited for use by persons of average and shorter than average height.

To achieve in part this dual mode of operation, the device 10 is characterized by having the diameter of the brush 14 substantially larger than the diameter of the wheels 16, 17. The brush diameter is preferably at least 25 percent larger than the diameter of the wheels but preferably not more than 75 percent larger. Taking into account constraints on gear sizes and other practical design limitations, if the brush diameter is significantly less than about 25 percent greater the diameter of the wheels 16, 17, the brush 15 will not engage the surface to be cleaned. when the device is in its inverted attitude. If the brush diameter is significantly more than about 75 percent greater than the diameter of the wheels, the handle elevations become extreme in one or both the operating attitudes of the device 10.

The device 10 will now be discussed from a different viewpoint. Referring particularly to FIG. 3, the device 10 is constructed such that a plane 60 containing the wheel axis 53 and intersecting the free end 62 of the handle 54 unequally divides the angle A defined by a tangential plane 64 on one side of the handle 54 and a tangential plane 66 on the opposite side of the handle 54. The tangential planes 64, 66 are defined as planes which are tangential to both the wheels 16, 17 and the brush 15.

The above-described dual mode of operation is also achieved in part by causing the axis of the brush shaft 15 to be off-set from the plane 60 such that a plane 68 intersecting both the brush shaft 15 and the wheel axis 53 makes a finite angle B with the plane 60 (see FIG. 3). By varying the magnitude of the angle B, the tangential planes 64, 66 are effectively caused to rotate in the same direction, thereby altering the manner in which plane 60 divides the angle A defined by planes 64, 66. As angle B is made greater, the difference in handle height from one operating mode to the other becomes greater. Angle B is easily varied during fabrication of the device 10 by altering the position of the apertures 52 in brackets 42, 44 which support the ends of the brush shaft 15.

Because the FIGS. 1-4 device is operated in both upright and inverted attitudes, it is desirable that the handle 54 accommodate the user in both of these operating modes. A handle having a free end 62 curved to accommodate the user's hand may be employed in combination with a swivel socket at the point where the handle 54 joins the housing 12 for the device. Alternatively, as shown in FIGS. 1, a straight handle 54 having a swiveling hand grip 70 may be employed. The hand grip 70 illustrated in FIG. 1 is exemplary of a great number of grip means which might be employed to achieve the stated result. The hand grip 70 is shown as comprising a generally tubular section 72 and a grip section 74. A retainer loop 76 prevents the grip 70 from sliding down on the handle 54. The tubular section 72 comprises a spine 78 and a plurality of bands 80 arranged in staggered relationship on opposite sides of the spine 78 to enable the grip 70 to be injection molded from suitable thermoplastic materials.

FIGS. 5-7 depict a sweeping device 81 representing a second embodiment of the invention which is similar to the FIGS 1-4 embodiment in general construction, operating and purpose, but different in the nature of its support structures. Like the FIGS. 1-4 embodiment the FIGS. 5-7 embodiment comprises a cylindrical brush 82 and a friction drive train which includes a pair of wheels, one of which is shown at 84, and a pair of spur gears 86, 88. Gear 86 is affixed to wheel 84 (or may be molded integrally therewith); gear 88 is attached to the shaft 90 of brush 82.

However, unlike wheels 16, 17 in the FIGS. 1-4 embodiment which are preferably carried on stub axles 18, 19, wheel 84 and its left end counterpart (not shown) are supported for rotation on shafts, one of which is shown at 92, which comprise part of a novel support structure for the device 81.

More particularly, the novel support structure of device 81 comprises a frame 94 which is rigidly affixed to (or an integral part of) a socket 96 for receiving a handle 98 for the device 81. Near each of its free ends, the frame 94 is reverse bent to produce at the extremities thereof, the shafts 92. The unit comprising wheel 84

and gear 86, and the left end wheel, have a central bore which receives the shafts 92 and are free to rotate thereon.

A multi-purpose housing 100, which may be of stamped sheet metal, for example, is attached to the frame 94 by welds, rivets, or by any other suitable connection method. The housing 100 has a number of functions which include: (1) shielding the user from flying dirt and degris; (2) adding structural rigidity (due to its curvature in planes transverse to the brush shaft 90) so as to allow the use of a lighter weight, less costly frame 94; (3) protecting the brush 82, wheels 84, and gears 86, 88; and (4) serving as a support for a pair of members, one of which is shown at 102, which function to support rotation the ends of brush shaft 90. In 15 the illustrated embodiment the members 102 take the form of thin walls fabricated, for example, from stamped sheet metal, which are fastened to forward and rear edges 104, 106, of the housing 100 by friction-fit clips (one of which is shown at 108). A flexible or 20 rigid trim strip (not shown) may be fastened on the edges 104, 106, if desired, to hide the clips 108 and serve as a bumper for the device 81.

End walls for the housing 100, one of which is shown at 110, have apertures for passing shafts 92. The end 25 walls 110 and brush-supporting members 102 cooperate to form open-sided chambers which provide some protection and dirt shielding for the transmission (gears 86, 88) and the wheels 84.

The FIGS. 5-6 device provides the same dual modes 30 of operation as described in detail above with respect to the FIGS. 1-4 embodiments.

The invention is not limited to the particular details of construction of the embodiments depicted, and it is contemplated that various and other modifications and 35 applications will occur to those skilled in the art. Therefore, because certain changes may be made in the above-described apparatus without departing from the true spirit and scope of the invention herein involved, it is intended that the subject matter of the above depiction shall be interpreted as illustrative and not in a 40 limiting sense.

As used herein, the term "stub axle" is intended to mean any means for supporting for rotation a single wheel or equivalent surface friction-driven member, as opposed, for example, to a transverse axle which might extend across a device for supporting a pair of wheels on opposite sides of the device. Thus, the shafts 92 in the FIGS. 5-7 embodiment are intended to be construed as stub axles.

Whereas the above depiction stresses the use of a rotary cleaning tool in the form of a cylindrical brush having bristle extending from a central shaft, the use of other surface-treating tools capable of rotary operation in lieu thereof is within the compass of this invention and such tools are intended to be considered as equiva-

lents thereof.

What is claimed is:

1. Ground and floor cleaning apparatus, comprising: a cylindrical brush having bristles extending from a central shaft; a pair of wheels mounted on respective stub axles, one wheel being disposed at each end of said brush; support means for rotatably supporting both ends of said brush shaft and for supporting said stub axles such that said wheels turn on a common wheel axis parallel with and forwardly of said brush shaft; transmission means coupling at least one of said wheels and said brush shaft such that wheel rotation causes brush to rotate in the opposite direction; and a handle joined to said support means such that said handle and said support means pivot together about said wheel axis, elevational adjustment of said handle effecting an adjustment of the interference between said brush and the surface being cleaned, whereby a user may control the bite of the brush instantaneously and continuously while operating the brush to compensate for variations in the characteristics of the debris being swept and of the surface being cleaned; said apparatus being characterized by having the diameter of said brush substantially larger than the diameter of said wheels and by being constructed such that a first plane containing said wheel axis and intersecting a manually engageable free end of said handle unequally divides an angle defined by a second plane tangential to said wheels and said brush on one side of said handle and a third plane tangential to said wheels and said brush on the other side of said handle, said brush being operable in a first attitude wherein said free end of said handle is in a relatively high operating position, or alternatively, in a second, inverted attitude wherein said free end of said handle is in a relatively low operating position.

2. The apparatus defined by claim 1 wherein said brush diameter is larger than said wheel diameter by about 25-75 percent.

3. The apparatus as defined by claim 1 wherein said support means comprises a housing means which includes a thin-walled, lightweight, rigid, plural function longitudinal body portion partially surrounding said brush to protect said brush and shield the user from flying debris, said body portion having substantial curvature in planes transverse to said brush shaft to provide structural rigidity for said housing means, said housing means including support means extending from body portion for effecting said support of said axle means and of said ends of said brush shaft.
